ACTIVITY TOY

Clayton Austin Laughlin, Minneapolis, Minn., assignor
to General Foods Corporation, White Plains, N.Y.

Filed Oct. 30, 1970, Ser. No. 25,748

Term of patent 14 years

Int. Cl. D21—01

U.S. Cl. D34—15

FIG. 1

FIG. 2

FIG. 1 is an isometric view taken from the top of an activity toy showing my new design;

FIG. 2 is an isometric view taken from the bottom, with the design turned 90° counterclockwise with respect to the orientation in FIG. 1;

FIG. 3 is a top plan view with depth of vision to the top frame member only;

FIG. 4 is a side elevation of the first side, with depth of vision to the middle of the bottom frame member only;

FIG. 5 is a side elevation of the second side, with depth of vision to the middle of the bottom frame member only;

FIG. 6 is a side elevation of the third side, with depth of vision to the middle of the bottom frame member only;

FIG. 7 is a side elevation of the fourth side, with

depth of vision to the middle of the bottom frame member only;

FIG. 8 is a bottom plan view with depth of vision to the bottom frame member only.

I claim:

The ornamental design for an activity toy, substantially as shown.
